FIG. 3.

UNITED STATES PATENT OFFICE.

ARTHUR ALEXANDER, OF BROOKLYN, NEW YORK.

GAME APPARATUS.

1,416,593.

Specification of Letters Patent. Patented May 16, 1922.

Application filed November 22, 1920. Serial No. 425,849.

To all whom it may concern:

Be it known that I, ARTHUR ALEXANDER, a citizen of the United States, and a resident of the city of New York, borough of Brooklyn, in the county of Kings and State of New York, have invented a new and Improved Game Apparatus, of which the following is a description.

My invention relates to a game apparatus in which stationary shooters and movable targets are employed.

The general object of the invention is to provide a novel game apparatus of such a character that a large number of players may engage in a contest and in which ball targets or equivalent target elements are dislodged from a traveling supporting structure, accumulated dislodged targets factoring in determining the winner of the game.

Reference is to be had to the accompanying drawings forming a part of this specification, it being understood that the drawings are merely illustrative of one example of the invention.

Figure 1 is a plan view of a game apparatus embodying my invention, parts being broken away;

Figure 2 is a longitudinal section of a shooter that may be employed;

Figure 3 is a vertical section as indicated by the line 3—3, Figure 1;

Figure 4 is a fragmentary perspective view of a portion of the apparatus on an enlarged scale;

Figure 5 is a detail in vertical section illustrating a supporting means that may be employed for the traveling target carrier.

In carrying out my invention in accordance with the illustrated example a fixed table 10 is provided which preferably is in the form of a round table and spaced from the table and in fixed position is a combined rail and gun mount structure 11 which preferably, in accordance with the round form of table 10, is of annular form and concentric with said table. The table 10 when of round form has a central opening 13 to accommodate an attendant. The table is formed into compartments which are radially positioned in the case of a round table, the compartments being formed by an inner wall 14, common to all the compartments, side walls 15, and a front wall 16.

The traveling carrier 12 has standards 17 or equivalent supports cup-shaped at the top to receive balls 18 so that the attendant

may place a ball on each standard, the standards advantageously in practice corresponding with the number of partitions. The outer fixed structure 11 is also divided into compartments corresponding with those of the table 10, the compartments being defined by an inner wall 19, an outer wall 20, and side walls 21.

Shooters are provided on the outer structure 11 at each compartment thereof. Each shooter 22 may consist of a barrel of suitable length having a plunger 23 therein provided with a plunger head 24 at the front, said plunger being acted upon by a coil spring 25 secured at its rear end as at 25^a to the gun at the rear of the bore thereof and secured at its front end as at 25^b to the head 24. Thus, the spring and head 24 are held positively within the barrel. Any suitable framework 26 may be provided for table 10 and fixed structure 11. The game is intended more particularly for use at summer resorts and in other public places and the structure will have a height so that players may use the apparatus while standing.

The structure 11 is spaced from the adjacent edge of the table 10 a sufficient distance to provide an intervening slot through which the standards 17 rise to a sufficient height above the table top and the partition walls to cause the balls 18 to travel in a plane to be dislodged by impact of a plunger 24. The target carrier 12 is in the form of a flat ring beneath and closing the space between the table 10 and the structure 11.

The traveling target carrier 12 which is manually turned is supported on rollers that it may be turned with facility and continue to move under its momentum and additional rollers are advantageously provided at the side edges of said carrier to prevent displacement of the carrier in its own plane. In the illustrated form vertical rollers 27, 27^a are provided near each side edge, said rollers turning on horizontal pins or screws 29 on blocks 30 secured respectively to the structure 11 and table 10 adjacent to the slot presented therebetween, said blocks being secured by vertical bolts 31, 31^a on which the horizontal rollers 28, 28^a are provided at the side edges of the carrier 12. 32 are nuts of bolts 31.

With a game apparatus constructed as described a player is stationed at each shooter 22 and therefore opposite a table compart-

ment, the object of each player being to dislodge the successive balls 18 from the traveling carrier as the balls pass individual shooters. The balls dislodged by a given shooter 5 will be retained in the compartment in line therewith and said compartments may have means factoring in the count of the game, there being shown five depressions in each compartment and therefore to each shooter 10 and these depressions may as indicated in Figure 4 be given different values; thus the pair of depressions nearest the shooter having for example the value 40, the two distant depressions, the value of 50, while the 15 centrally disposed depression may have the value of 100.

One table compartment indicated as at A in Figure 1 and the corresponding compartment B of the outer structure 11 may respectively be free of the depressions and shooter and a second attendant may be stationed adjacent the compartment B at the outside of structure 11 for collecting the entrance fee for partaking in the game and 25 generally looking after the convenience of the players or affording any needed guidance or instruction to the players.

The shooters 22 in the preferred form of the invention are stationary, the same being 30 pivotally mounted on gun mounts 22^a on the structure 11 but obviously portable shooters may be employed.

I would state in conclusion that while the illustrated example constitutes a practical embodiment of my invention, I do not limit myself strictly to the mechanical details herein illustrated, since manifestly the same can be considerably varied without departure from the spirit of the invention as defined in the appended claim.

Having thus described my invention, I claim:

An apparatus of the class described including a table, a structure adjacent to said table at which players may station themselves, said structure and table being spaced to present a slot therebetween, shooters mounted on said structure and disposed toward the table, a traveling target carrier in the form of a flat ring beneath and forming a closure of said slot, said ring extending beneath both the said structure and said table, and rollers on the table and on said structure at the under side, on which rollers the said ring is supported at each side laterally of said slot, and target supports on said carrier between the table and said structure adapted to receive targets for carrying the targets past the shooters between said shooters and the table, said shooters adapted to be projected into the path of movement of the targets for dislodging the latter.

ARTHUR ALEXANDER.
